(57) **CLAIM**

The ornamental design for a fork, as shown and described.

DESCRIPTION

FIG. 1 is a front, right side perspective view of a fork, showing our new design;

FIG. 2 is a back, left side perspective view of the fork of FIG. 1;

FIG. 3 is a front, left side perspective view of the fork of FIG. 1;

FIG. 4 is another front, left side perspective view of the fork of FIG. 1;

FIG. 5 is a front elevational view of the fork of FIG. 1;

FIG. 6 is a back elevational view of the fork of FIG. 1;

FIG. 7 is a left side elevational view of the fork of FIG. 1;

FIG. 8 is a right side elevational view of the fork of FIG. 1;

FIG. 9 is a top view of the fork of FIG. 1; and,

FIG. 10 is a bottom view of the fork of FIG. 1.

The dashed broken lines and the dot-dash-dot broken lines depict environment, and the elements shown in the dashed broken lines and the dot-dash-dot broken lines form no part of the claimed design.

1 Claim, 9 Drawing Sheets
